US00D969247S

(12) **United States Design Patent** (10) **Patent No.:** **US D969,247 S**
(45) **Date of Patent:** **** Nov. 8, 2022**

(54) **TUBING COMPONENT**

(71) Applicant: **P&P IMPORTS LLC**, Irvine, CA (US)

(72) Inventors: **Peter Engler**, Newport Beach, CA (US); **Peter Tanoury**, Newport Beach, CA (US)

(**) Term: **15 Years**

(21) Appl. No.: **29/833,720**

(22) Filed: **Apr. 6, 2022**

Related U.S. Application Data

(63) Continuation of application No. 29/727,386, filed on Mar. 10, 2020, now Pat. No. Des. 953,458.

(57) **CLAIM**

The ornamental design for a tubing component, as shown and described.

DESCRIPTION

FIG. 1 is a perspective view of a tubing component showing our new claimed design;

FIG. 2 is a right-side elevational view thereof, the left-side elevational view being a mirror image thereof;

FIG. 3 is a back elevational view thereof;

FIG. 4 is a front elevational view thereof;

FIG. 5 is a top plan view thereof;

FIG. 6 is a bottom plan view thereof; and,

FIG. 7 is a perspective view of the tubing component shown in an environment of use.

Broken lines in FIGS. 1-6 show portions of the tubing component that form no part of the claimed design. Broken lines in FIG. 7 show environmental subject matter that forms no part of the claimed design.

1 Claim, 7 Drawing Sheets
